UNITED STATES PATENT OFFICE.

GEORGE HENRY OATWAY AND CHARLES EDWARD MAY, OF LONDON,
ENGLAND.

FIRE-ALARM.

No. 828,542.

Specification of Letters Patent.

Patented June 19, 1906.

Application filed April 3, 1905. Serial No. 253,555.

To all whom it may concern:

Be it known that we, **GEORGE HENRY OATWAY**, managing director of The May-Oatway Fire Appliances, Limited, and **CHARLES EDWARD MAY**, director of The May-Oatway Fire Appliances, Limited, subjects of the King of Great Britain, residing at 92 and 94 Paul street, in the city of London, England, have invented certain new and useful Improvements in Fire-Alarms, of which the following is a specification.

This invention relates to fire-alarms of the class in which an electric circuit is closed or opened or an alarm otherwise given by the expansion and consequent slackening of a wire. Alarms of this class are described in the British specifications, No. 23,018 of 1900 and No. 5,984 of 1901.

In order to obtain certainty of working with such apparatus and to prevent false alarms caused by vibration, it is necessary for the expansion of the wire in case of fire to be sufficient to considerably increase its length, and this has heretofore involved the use of a somewhat long wire, which is sometimes inconvenient.

The object of the present invention is to obtain the necessary slackening with a much shorter wire. For this purpose the end of the wire instead of being fixed to the base as before is attached to the long arm of a lever, the shorter arm of which is pivoted to one end of a metallic rod whose other end is fixed to the base, so that the expansion of the bar turns the lever about its pivot, and so slacks the wire, thus adding to the slackening caused by its own expansion. The wire may be replaced by a cord or the like which does not expand with heat; but this is not usually desirable. In this specification such a cord or the like is included under the term "wire."

The rod may be replaced by a tube or even by a flexible wire if the latter is always kept in tension by a sufficient strain on the other wire. In this specification such a tube or wire is included under the term "rod."

The base upon which the whole arrangement is carried preferably consists, as is usual, of a bar or frame which acts as a compensator by expanding approximately equally with the other parts when the rise of temperature is slow, thus preventing false alarms.

Figure 1 is an elevation of an apparatus

constructed according to this invention, and Fig. 2 is a similar view of its two ends to a larger scale. Fig. 3 is a view similar to Fig. 1, but in addition showing one way in which the device may be employed to close a signaling-circuit.

a is a plate forming the base of the apparatus and serving as the compensator.

b is the wire. Its end *b'* is fixed to one arm of a lever *b²*, whose movement is limited by a stop *b³*, the wire being kept at the proper tension by a weight *b⁴*, hung from the other arm of the lever. The efficiency of the apparatus can be tested at any time by raising the weight *b⁴*, and so slackening the wire. The end *b⁵* of the wire is connected to the long arm of the lever *c*, pivoted at *c'* to the plate *a*.

d is a rod of metal having its end *d'* fixed to the plate *a* and its other end *d²* pivoted to the short arm of the lever *c*.

The contacts or mechanism by which the wire *b* gives the alarm form no part of this invention and are not shown. They may be of any convenient form and are preferably connected with the wire *b* through a link or eyelet held in position by solder compounded to melt and let go when some predetermined temperature is reached.

When the temperature of the room rises gradually, the plate *a*, the wire *b*, and the rod *d* all expand approximately equally, so that the droop of the wire *b* remains substantially constant, and until the temperature is reached at which the solder lets go no alarm is given. When, however, a fire takes place and the temperature of the room rises rapidly, the rod *d* and wire *b* (if it be metallic) expand more quickly than the plate *a*. The expansion of the rod *d* in this case turns the lever *c* about its pivot, thereby slackening the wire and increasing the slackening caused by its own expansion, with the result that an alarm is given before the temperature rises sufficiently to cause the solder to let go.

In Fig. 3 a contact-making bob *X* is shown connected with the wire *b*. This bob is adapted to engage contact-fingers *Y Y'*, which are connected to wires *y y'* of a signaling-circuit, which is normally open at the contacts *Y Y'*. When the wire *b* expands, the bob *X* drops into contact with the fingers *Y Y'* and closes the circuit and gives the alarm.

What we claim is—

1. The combination of a compensator or

base constructed to expand approximately equally with the other parts of the apparatus when the rise of temperature is slow and which is exposed to changes in the atmosphere, a lever pivoted to the base, a quickly-expansible rod having one end fixed to the base and the other end pivotally connected with one arm of the lever and a flexible wire having one end connected to the base and the other end to the other arm of the lever.

2. The combination of a compensator or base constructed to expand approximately equally with the other parts of the apparatus when the rise of temperature is slow and which is exposed to changes in the atmosphere, but to expand more slowly than the other parts when the rise of temperature is sudden, a lever pivoted to the base, an expansible rod having one end fixed to the base and the other end pivotally connected with one arm of the lever, and an expansible and flexible wire having one end connected to the base and the other end to the other arm of the lever.

3. The combination of a compensator or base constructed to expand approximately equally with the other parts when the rise of

temperature is slow, but to expand more slowly than the other parts when the rise of temperature is sudden, an expansible rod having one end fixed to the base and the other to one arm of the lever, a weighted lever pivoted to the base and a wire having one end connected to the weighted lever and the other end to the other arm of the first lever.

4. The combination of a compensator or base constructed to expand approximately equally with the other parts of the apparatus when the rise of temperature is slow, but to expand more slowly than the other parts when the rise of temperature is sudden, an expansible rod having one end fixed to the base and the other end pivoted to one arm of the lever, a weighted lever pivoted to the base and an expansible wire having one end connected to the lever and the other end to the other arm of the first lever.
